UNITED STATES PATENT OFFICE.

FREDERICK AXT, OF FRANKLIN, INDIANA.

GUTTER BOX OR TROUGH.

SPECIFICATION forming part of Letters Patent No. 320,324, dated June 16, 1885.

Application filed May 6, 1885. (No model.)

To all whom it may concern:

Be it known that I, FRED. AXT, a citizen of the United States, residing at Franklin, in the county of Johnson and State of Indiana, have invented a new and useful Improvement 5 in Gutter Boxes or Troughs to hold Eaves Gutters or Troughs, of which the following is a specification, reference being had to the accompanying drawings.

10 My invention relates to an improvement in gutter boxes or troughs to hold eaves gutters or troughs while soldering in suitable lengths; and it consists in the peculiar construction and combination of devices, that will be more fully 15 set forth hereinafter, and particularly pointed out in the claims.

In the accompanying drawings, Figure 1 is a perspective view of a box or trough embodying my invention. Fig. 2 is a vertical trans- 20 verse sectional view of the same. Figs. 3 and 4 are detail views.

A represents a box or trough, which is semi-hexagonal in shape on its outer side, and is semi-cylindrical in shape on its inner side, as 25 shown. The side B of the trough is slightly lower than the side C.

E represents a series of racks actuated by springs S, which racks are secured on the outer side of the side C of the trough and extend 30 for a suitable distance above the upper edge thereof, and are hinged to allow them to move in and out. F represents a series of presser-arms, which are hinged to the side B of the trough by means of the hinges G. These 35 hinges are provided with vertical slots H, through which pass screws I, that secure them to the trough. By means of this construction the hinges may be raised or lowered in the countersunk mortises which are made to receive them, so as to raise or lower the inner 40 ends of the presser-levers F with respect to the upper edge of the side B, in order to adapt the box or trough to be used to fit any size bead. On the outer under ends of the levers 45 F are secured the flat bearing-springs K, fastened with screws or rivets P. Slots L are made in the outer ends of these levers, and through these slots pass set-screws K', which secure bits M in the outer end of the levers, 50 which bits engage with the racks E. By means of the slots and set-screws the bits may be

taken out or adjusted from the ends of the presser-levers, so as to compensate for wear on the ends of the bits, or to sharpen them when necessary. The upper edges of the sides 55 B and C are sheathed with steel or other suitable metal, as at N. The racks E and the hinges G are countersunk in the sides of the trough, so as to enable it to be tilted so as to place said trough in a convenient position for 60 soldering.

The operation of my invention is as follows: The trough is made a sufficient length to accommodate any desired number of lengths of the eaves troughs or gutters that are to be 65 joined together. In Fig. 2 of the drawings, z represents the eaves-trough after it has been bent in shape in dotted lines, the trough being formed on one side with the bead a in the usual manner upon the ordinary beading-machines. 70 This bead rests upon the upper side of the side B, and the jointed ends of the sections of the eaves-trough are placed under the inner end of the presser-levers. When the levers are pressed down, their inner ends hold the bead 75 between them and the upper edge of the side B, and hold them together in shape for soldering, as will be readily understood. The outer ends of the presser-levers are engaged by the spring-actuated racks E and held in 80 position, as will be readily understood. As the levers are being pressed down to hold the gutter in the box, the springs K serve to steady and regulate the pressure on the edge of the eaves-trough, and avoid mashing and 85 injuring the tin.

This box or trough is very compact, cheap, and simple, and is thoroughly efficient in operation.

Having thus described my invention, I 90 claim—

1. The combination of the trough A, the presser-levers F, hinged thereto, and the spring-actuated racks E, for engaging the free 95 ends of the presser-levers, substantially as described.

2. The combination of the trough A, the slotted hinges G, secured thereto, the presser-levers secured to said hinges, and the spring-actuated racks for engaging the outer ends of 100 the levers, substantially as described.

3. The combination of the trough A, the

presser-levers hinged thereto, said levers being provided with the bearing-springs K on the under sides of their outer ends, and the spring-actuated rack for engaging the free ends of the levers, substantially as described.

4. The combination of the trough A, the presser-levers hinged thereto, the outer ends of the levers being provided with the slots L, the bits M, and set-screws K', and the

spring-actuated racks engaging with the bits, substantially as described.

In testimony that I claim the foregoing as my own I have hereto affixed my signature in presence of two witnesses.

FREDERICK AXT.
